UNITED STATES PATENT OFFICE.

LAROY S. STARRETT, OF ATHOL, MASSACHUSETTS.

HAMMER.

1,258,053.

Specification of Letters Patent.

Patented Mar. 5, 1918.

Application filed August 2, 1915. Serial No. 43,105.

To all whom it may concern:

Be it known that I, LAROY S. STARRETT, citizen of the United States, residing at Athol, county of Worcester, Commonwealth 5 of Massachusetts, have invented certain new and useful Improvements in Hammers, of which the following is a specification.

This invention relates to hammers and the like and particularly to a nail placing attachment therefor.

My present invention is in the nature of an improvement on my former patent, dated December 1, 1903, No. 745,973, and is designed to remedy certain difficulties in the 15 use of said former hammer by doing away with the slot back of the nail head which was liable to get battered and close up, thereby interfering with the action of the spring.

The present invention contemplates a nail 20 placer which will positively hold the nail (before starting) and will permit instant release of the nail after the starting blow is struck by a simple movement of the hammer itself.

25 The construction and operation of my device will be more fully described in the specification which follows. In the drawings accompanying that specification, I have shown two forms of my invention which 30 not only clearly illustrate the principles involved, but are in themselves constructions found satisfactory and well adapted to the requirements of manufacture. Throughout specification and drawings like reference 35 numerals are employed correspondingly, and in these drawings:

Figure 1 is a plan section on the line 1—1 of Fig. 2, of a hammer equipped with one form of my nail placing attachment,

40 Fig. 2 is an elevation of the hammer head, Fig. 3 is an end view thereof,

Fig. 4 is a detail section on the line 4—4 of Fig. 3,

Fig. 5 is a detail view of the spring tensioned pivot for the nail placer,

Fig. 6 is a perspective view of the operating device for the nail placer,

Fig. 7 is a view corresponding to Fig. 2 of a modified form of nail placer,

50 Fig. 8 is an end view of Fig. 7,

Fig. 9 is a detail section on the line 9—9 of Fig. 10, and

Fig. 10 is a detail section on the line 10—10 of Fig. 8.

55 In the form of my invention shown in

Figs. 1 to 6, inclusive, the poll 1 of the hammer head 2 is provided along its top face with a shallow groove 3 in which the shank of a nail 4 is received with the head 5 of the nail received in a transverse recess 6 across 60 the poll behind the groove 3. Beyond the recess 6 the poll is formed as an enlarged bearing 7 having a vertical driving wall 7¹ against which the head of the nail abuts. The bearing 7 has a transverse bore 8 and a 65 longitudinal groove 9 across its top face connecting with said bore 8.

Rotatably mounted in the bore 8 is a spring wrapped pivot pin 10. The pin 10 is reduced between its ends and has a coil 70 spring 11 wrapped about its reduced portion. One end of the spring 11 is received in a groove formed in the body of the pin and the other end of the spring is received in a groove formed in the bearing 7. 75

Fastened to the pin 10 between its ends in any suitable manner is a nail holder 12. The nail holder 12 is received in the groove 9 formed in the bearing 7 with its free end normally lying in the groove 3 at the free 80 end of the poll. The groove 9 and nail holder 12 therefore prevent lateral displacement of the pin 10 in its bore 8. The free end of the member 12 may be concaved slightly as indicated at 12¹ to conform to 85 the shank of the nail.

Let diagonally through the poll 1 from the underside thereof is a bore 13 terminating at its lower end in an enlarged recess 14. Reciprocable in the bore 13 is a release 90 pin 15 having a head 16 disposed to engage the under face of the member 12 and terminating at its opposite end in an enlarged head 17 exposed beyond the recess 14 as an operating end and received in said recess 14 95 when pushed upwardly.

In using this form of my invention, the nail holder 12 is raised to permit the nail 4 to be placed in the groove 3 of the poll 1 with its head 5 received in the cross groove 100 6. The nail holder 12 may be raised by applying the thumb to the exposed end 17 of the operating device 15 and pushing said device upwardly. This lifts the member 12 and effects a partial rotation of the pivot 105 pin 10 against the action of the spring 11. As soon as the pressure on the member 15 is lifted the spring returns the member 12 to frictionally clamp the nail, thereby moving the plunger 15 back to original position. 110

With the nail thus in position, a blow is struck with the hammer. The bearing of the nail head 5 against the vertical wall 7¹ of the bearing 7 drives the nail forward. The nail 5 may then be removed from the hammer by simply drawing the hammer downward, the member 12 yielding to permit the nail to be disengaged. The nail is now started and may be driven in the usual manner.

10 In the form of my invention shown in Figs. 7 to 10 inclusive, the poll 1 is grooved along its under face as indicated at 18 and beyond its longitudinal groove has an enlarged cross groove 19 to receive the head 5 of the nail. The purpose of the under cut groove 18 is to receive a nail which is slightly bent between its ends. The rear side of the groove 19 extends as a vertical wall 20 against which the head 5 of the nail bears and which wall delivers the impact to the nail in starting. Pivoted to the wall 20 between its ends at 21 is a finger lever 22. The free end 22¹ of the lever 22 engages the nail and holds it in place against the under face 25 of the poll. The opposite end of the lever 22 extends downwardly adjacent the hammer handle 2¹ as a thumb operating portion 23. Fastened to the portion 23 is a blade spring 24 which is bent to conform to the portion 23 and has its free end in contact with the handle 2¹ of the hammer.

30

In using the nail placer of this form of my invention, the finger lever 22 is pressed inwardly toward the hammer handle to cause its nail engaging portion 22¹ to rock downwardly away from the poll. The nail 4 is then placed in position against the under face of the poll 1 with its head 5 received in the groove 19. The finger lever is then 35 released and the spring 24 throws the nail engaging portion 22¹ thereof up against the nail to frictionally clamp it in position. The nail is started by a blow with the hammer, the wall 20 driving the nail. The nail is 40 released by moving the hammer away from the nail, the member 22 yielding slightly to permit this disengagement. The nail is then 45 driven home in the usual manner.

While I have shown and described my nail placer in its application to a hammer it will 50 be understood that the device may be adapted to other tools without departing from the spirit of my invention.

Various other modifications in the form 55 and construction of my device may obviously be resorted to without departing from the spirit of my invention if within the limits of the appended claims.

What I therefore claim and desire to secure by Letters Patent is:

1. In combination with a driving implement having a nail receiving groove, a pivoted clamping member having a concaved nail engaging end overlying said groove, 60 means for maintaining said end in effective

relation to said groove, and a plunger for displacing said member to permit a nail to be laid in said groove.

2. In combination with a driving implement having a supporting portion for an article to be driven, a member normally disposed in clamping relation to an article positioned upon said supporting portion, a rotatable mount for said member permitting movement of said member away from said supporting portion, a spring associated with said mount and normally effective to maintain said clamping member in article clamping relation, and a plunger disposed transversely to said clamping member for swinging said clamping member away from said article supporting portion to permit an article to be positioned thereon.

3. In combination with the poll of a hammer or other driving implement, said poll having a nail receiving groove and having an enlarged bearing bored transversely and grooved longitudinally, a nail clamping member guided in said longitudinal groove of the poll and having an end effectively disposed relative to said nail receiving groove, having a pivot for said clamping member mounted in said transverse bore of the poll and permitting movement of said member relative to said nail receiving groove, 90 said clamping member and guiding groove co-operating with the walls of said bearing adjacent said groove to prevent lateral displacement of said pivot, and a reciprocable plunger disposed for engagement with said clamping member for moving said member away from said nail receiving groove to permit a nail to be laid therein.

4. In combination with a driving implement having a supporting portion for an article to be driven, a pivoted clamping member adapted to releasably engage said article and a plunger mounted in the implement transversely to the supporting portion and perpendicular to the clamping member, and adapted to engage said member between its ends to move it away from said supporting portion, thereby to permit an article to be driven to be positioned upon said supporting portion.

5. In combination with a driving implement having a rigid head seat and a groove for a nail or the like, a nail clamp mounted to swing toward and away from said groove and a manually operable pin mounted transversely in the implement head and longitudinally movable against the clamp to move said clamp away from the groove, thereby to permit the insertion of a nail in said groove.

6. In combination with a driving implement having a nail receiving groove, a member having an end effectively disposed relative to said groove, yielding automatic means for maintaining said end in effective

relation to said groove and a manually operable plunger projecting through the head of the implement and disposed perpendicularly to said movable member for moving said member away from said groove to permit a nail to be laid in said groove.

7. In combination with a driving implement having a nail receiving groove, a nail clamping member pivotally mounted for movement toward and away from said groove, a spring about the pivot for said member and normally opposing movement thereof away from said groove and adapted to return said member toward said groove, and reciprocable means for moving said clamping member against the action of said spring away from said groove and said means itself returned to original position by the said spring acting through said clamping member.

8. In combination with a driving implement having an article receiving groove terminating in a rigid head seat on the imple-

ment, and having a guiding bore extending through the implement transversely to the 25 groove, a movable article clamping member effectively disposed relative to said groove and an operating device reciprocable in said guiding bore and having an end adapted to engage said clamping member and having 30 an exposed operating end.

9. A hammer having the usual poll, one side of said poll being provided with a nail seat, a yielding clamp in opposition to said seat and mounted on the hammer body, and 35 means having a portion exposed for manual engagement on the opposite side of the poll, for lifting said clamp from effective clamping position to permit the insertion of a nail into the seat.

In testimony whereof I affix my signature in presence of two witnesses.

LAROY S. STARRETT.
